METHOD AND APPARATUS FOR SURFACING
SHEET MATERIAL

John A. Soissa, Savannah, Ga., assignor to Certain-Teed Products Corporation, New York, N. Y., a corporation of Maryland

Application March 20, 1940, Serial No. 324,970

7 Claims. (Cl. 117—19)

This invention relates to methods of and machines for applying comminuted or granular surfacing materials to a web. The invention more especially relates to surfacing with comminuted material a roofing web which carries a coating of adhesive water proofing material.

Such webs and roofing materials have been made with surfacing materials applied thereto so as to adhere to the adhesive coating. Different colors and many different arrangements of the colors have been used to produce variegated and multi-color roofing sheets and shingle elements. A problem which arises in the manufacture of such webs and roofing materials is that of effecting changes of the colors without loss of the granular material or contamination thereof by intermixture of the differently colored granular materials and without loss of time.

It has been the practice in the roofing industry to surface the moving web from a hopper adjacent the coated face of the web and to partially embed the granular surfacing material in the coating by passing the surfaced sheet into circumferential contact with a revolving drum adjacent the hopper. The hopper has been arranged near the drum and a doctor has been provided to guide to the hopper the off-fall from the drum of granular material applied to the web in excess of that required to completely cover and adhere to the surface of the web.

When manufacturing a mineral surfaced roofing sheet, however, with longitudinal bands of different colors of the comminuted material difficulties have been encountered in returning, by means of the doctor, the off-fall from the drum to the proper compartments provided in the supply hopper for the different colors which have resulted in partial intermixture of the granular materials intended for adjacent longitudinal bands on the web and in the consequent modification of the colors of the granular material in the respective adjacent compartments of the hopper due to this mixing.

It is an object of this invention to provide an economical method of surfacing a web to eliminate the above described difficulties.

It is the further object of the invention to provide a method of surfacing a roofing web, and apparatus for carrying out the method, which allows rapid change of the color of the comminuted materials deposited on the web while the web is continuously moved in the direction of its length.

It is a further object of the invention to effect this change in colors without undue overlap of

the colors, or on the other hand without leaving any substantial portion of the length of the web unsurfaced with granular material.

It is a further object of the invention to effect the change in color without intermixture of the colors and without undue loss of granular material.

Another object of this invention is to provide apparatus for surfacing a roofing web which effects return of excess granular material from the surface of the web to the hopper, and to the proper compartments of the hopper positioned transversely across the web, with substantially no modification of the color of the supplies by the blending of the "returns."

It is a primary feature of my invention that the excess granular material applied to the sheet is returned directly to the supply without the use of intermediate baffles or guide means in the path of flow of the excess granular material.

It is a further feature of my invention that the supply is moved out of the path of flow of the excess granular material when it is desired to change the character of the material in the supply. I may provide means to intercept the excess material in said path of flow when said supply is removed from the path, which means may also be effective to receive from said supply in its removed position granular material discharged toward the surface of the web and before it reaches the surface of the web.

Another feature of my invention is the provision of an auxiliary fixed supply which may be placed along the web from said movable supply and which may contain different color comminuted material. I may use this auxiliary supply when it is desired to change the color of comminuted material being applied to the face of the roofing sheet.

In carrying out my improved method of surfacing a roofing web having a face adapted to bond thereto granular material I provide for movement of the web in the direction of its length across the paths of delivery of granular materials from the movable supply and from the auxiliary supply. I feed granular material from the main supply, that is, this movable supply continuously toward the face of the web in excess of the quantity required to adhere to and completely surface it, and I position this movable supply so that it directly receives without the intervention of a doctor or baffle the excess granular material returned from the surface of the web.

When it is desired to change the color of

granular material being applied to the web, I fill the auxiliary supply with the granules of different color. When the main supply is about to be exhausted I initiate feed of the granular material from the auxiliary supply toward the face of the web and then move the main supply out of the return path of flow of the excess material from the web so that it no longer receives the "returns." To avoid deposition of the "returns" on the web I may intercept these "returns" and convey them to one side of the web. When the main movable supply is empty and the new granules of different color are returned I again move this supply to the position where it intercepts the path of flow of the returned excess granular material and I replenish the main supply with the same color granular material as that of the auxiliary supply. As this auxiliary supply approaches exhaustion, I again initiate feed from the main supply and continue feeding from the auxiliary supply until feed therefrom ceases. The main movable supply then continues the surfacing of the web.

A detailed description of my improved surfacing method and apparatus together with other objects and advantageous features will be given in connection with the drawing in which

The figure is a diagrammatic representation of surfacing apparatus embodying the elements of my invention.

In the figure, the web 2 may be a roofing sheet having on the upper face thereof an adhesive coating of waterproof material such as asphalt. The web 2 is caused to be moved toward the right-hand side of Figure 1 under the action of revolving drums 4 and 6.

Supported above the surface of the web 2 by tracks 8 is shown a main hopper 12. Projections 14 are provided on the sides of hopper 12 bearing on track 8 to permit movement of the hopper to a position adjacent the surface of the drum shown in full outline and to a position remote therefrom shown in dotted outline.

A feed roller 16 is shown associated with the outlet opening 18 of the hopper 12 to effect delivery of granular material therefrom. The feed roll 16 may be rotated by suitable means not forming part of the invention so as to rotate the feed roll 16 counterclockwise when the hopper 12 is adjacent the drum 4 and to rotate the roll 16 clockwise when the hopper 12 is positioned remote from the drum as shown in dotted outline. A gate 17 and a baffle 19 are provided on the hopper 12 for purposes to be explained below. It can be seen from the drawing that the hopper 12 when positioned adjacent the surface of the drum 4 may receive off-fall of excess granular material directly from the drum, no intermediate guides or baffles being necessary.

Positioned adjacent the drum 4 but out of the path of delivery toward the web of granular material from the hopper 12 in its position adjacent the surface of the drum is shown a conveyor 20 having a belt 22 driven by any suitable means in a direction transverse to the movement of the web 2.

The conveyor 20 is positioned to receive the otherwise unintercepted off-fall from the drum 4 when the hopper 12 is in the position shown in dotted outline. It also may receive granular material from said hopper in said position shown in dotted outline when the feed roll 16 is revolved in the clockwise direction. In addition gate 17 in the hopper 12 may be opened when said hopper 12 is positioned remote from the drum 4 to permit

the contents thereof to be quickly dumped over the baffle 19 into the conveyor 20. It will be noted that the baffle is carried by the hopper structure to move therewith so as not to interfere with movement of the hopper 12.

5 An auxiliary hopper 24 having an outlet opening 26 and a feed roll 28 associated therewith is supported by means not shown above the web and conveniently spaced from the main hopper 12 along the web.

10 Generally indicated at 30 is conventional mechanism for applying mica or other anti-stick material to the reverse side of the web.

The operation of my apparatus in the particular embodiment shown is as follows:

15 Hopper 12 is positioned adjacent the drum 4 and is filled with granular material of suitable color. Drums 4 and 6 are revolved in the direction shown and web 2 is moved toward the right of the figure. Feed roller 16 is revolved in the 20 counterclockwise direction and granular material from hopper 12 is deposited on the surface of the roofing web 2 in excess of the amount required to completely cover and adhere to the web. The surfaced web 2 then passes around the drum 4 and the granular material is partially embedded in the face of the web 2. The excess comminuted material is carried over the surface of the drum 4 and falls toward the sheet 2 but directly into the hopper 12.

25 30 When it is desired to change the character of granular material applied to the surface of the web 2, the supply of granular material in the main hopper 12 is allowed to become almost exhausted, the auxiliary hopper 24 meanwhile having been filled with granular material of the different color or character. Feed from the auxiliary hopper 24 by means of feed roll 28 is then initiated before the discharge of material from the hopper 12 ceases and so that no bare unsurfaced areas will be left on the web 2.

35 40 The hopper 12 is then moved to the position shown in dotted outline and off-fall of excess granular material of the first color from the drum is received in the conveyor 20. When the hopper 12 is moved to said position remote from the drum, the direction of rotation of feed roll 16 thereof is changed to clockwise and the gate 17 is swung open as shown in dotted outline and the material remaining in hopper 12 is quickly dumped into the conveyor 20 and is carried on belt 22 to one side of the web where it may be disposed of in any convenient manner.

45 50 55 When the main hopper 12 is emptied and the excess granular material off-falling from the drum 4 becomes of the same color as that in the auxiliary hopper 24 the gate 17 is closed and the hopper 12 is moved into position to again intercept the path of flow of the off-fall material from the drum 4. The main hopper 12 is then quickly filled from the storage supply with granular material of the same character as that in the auxiliary hopper 24 and feed from said main hopper toward the web is started as said auxiliary hopper approaches being empty. The main hopper 12 is replenished in the usual manner from time to time from the storage supply of granular material to keep it from becoming empty.

60 65 70 75 If it is desired to lay parallel longitudinal bands of different colors on the face of the web 2 the hoppers 12 and 24 may each be divided into compartments across the sheet containing granular material of different colors in the manner well known in the roofing art. In this embodiment the direct return of the off-fall to the proper com-

partment and avoidance of intermixture of the colors of adjacent color bands, with consequent elimination of modification of the colors of the granular material in the compartments, is assured by virtue of the hopper 12 being immediately adjacent the surface of the drum 4. Spread of the off-falling returns into adjacent compartments is thereby prevented. The arrangement of the hopper 12 so as to be movable out of the path of these returns makes it possible to separately collect them, however, when a color change is made and thereby keeps them from contaminating the new color.

In the description and in the claims by the term granular material of different colors I mean comminuted materials of different physical characteristics, such as size, appearance, color, texture, or other qualities which produce different effects on the finished roofing web.

It is understood that roofing made according to my invention may be further processed to produce strips or shingles by apparatus and processes well known in the art.

Having thus described my invention, I now claim:

1. The method of surfacing a web which comprises moving in the direction of its length a web capable of bonding granular material to a face thereof, feeding granular material from a supply to said face of the web in excess of the quantity required to cover and adhere to said face, returning to said supply in a given path of flow the excess of said granular material from said face of the web, moving said supply out of said path of flow after a portion of said web has been covered with granular material fed from said supply, intercepting flow of granular material in said path of flow of said excess material, and conveying said intercepted material away from the surface of said web.

2. The method of surfacing a web which comprises moving in the direction of its length a web capable of bonding granular material to a face thereof, feeding granular material from a supply to said face of the web in excess of the quantity required to cover and adhere to said face of the web, returning to said supply in a given path of flow the excess of said granular material from said face of the web, moving said supply out of said path of flow of said excess granular material, and initiating feed of granular material of different color toward said face of said web from an auxiliary supply at a time before said first supply becomes exhausted which prevents substantial overlap of or space between the differently colored granular surfacings on said web.

3. Apparatus for surfacing with granular material sheet material having a face thereof capable of bonding the granular material thereto comprising means for moving the sheet substantially in the plane of its extent, a container providing a supply of granular material, means for withdrawing granular material from said container and feeding it to said face of said moving sheet in excess of the quantity required to cover and become bonded to said face of the sheet, means for removing the excess granular material from said face and causing it to flow in a given return path toward said container, and means for supporting said container so as to be movable into and out of said return path of flow of said excess granular material.

4. Method of surfacing a web which comprises moving in the direction of its length a web capable of bonding granular material to a face thereof, feeding granular material from a supply to said face of the web in excess of the quantity required to cover and adhere to said face, removing said excess granular material from said face of the web and causing it to move in a given path of return flow toward said web which includes said supply of granular material, moving said supply out of said path of flow after a portion of said web has been covered with granular material fed from said supply, and thereafter intercepting flow of granular material in said path of flow of said excess material and preventing said excess material from reaching said web.

5. Method of surfacing a web which comprises moving in the direction of its length a web capable of bonding granular material to a face thereof, feeding granular material from a supply to said face of the web in excess of the quantity required to cover and adhere to said face, removing said excess granular material from said face of the web and causing it to move in a given path of return flow toward said web which includes said supply of granular material, moving said supply out of said path of flow after a portion of said web has been covered with granular material fed from said supply, thereafter intercepting flow of granular material in said path of flow of said excess material and preventing said excess material from reaching said web, and initiating feed of granular material of different color toward said face of the web from an auxiliary supply at a time before said first supply becomes exhausted to prevent space between the different colored granular surfacings on said web.

6. Method of surfacing a web which comprises moving in the direction of its length a web capable of bonding granular material to a face thereof, feeding granular material from a supply to said face of the web in excess of the quantity required to cover and adhere to said face, collecting the excess granular material from said face of the web and returning it toward the web through a return path which includes the supply of granular material, maintaining said return path until a portion of the web has been covered with granular material, and thereafter varying the return path so that excess material will not be returned to said web.

7. Method of surfacing a web which comprises moving in the direction of its length a web capable of bonding granular material to a face thereof, feeding granular material of a given color from a supply to said face of the web in excess of the quantity required to cover and adhere to said face, collecting the excess granular material from said face of the web and returning it toward the web through a return path which includes the supply of granular material, maintaining said return path until a portion of the web has been covered with granular material, thereafter varying the return path so that excess material will not be returned to said web, and initiating feed of granular material of different color toward said face of the web from an auxiliary supply at a time before said first supply is discontinued whereby no space will be left on the web between the differently colored granular surfacings.

JOHN A. SOISSA.
